UNITED STATES PATENT OFFICE.

JOHN G. LYON, OF PITTSBURG, PENNSYLVANIA, ASSIGNOR TO THE O'HARA GLASS COMPANY, LIMITED, OF SAME PLACE.

DESIGN FOR AN ASH-RECEIVER.

SPECIFICATION forming part of Design No. 17,181, dated March 15, 1887.

Application filed December 29, 1886. Serial No. 222,431. Term of patent 7½ years.

To all whom it may concern:

Be it known that I, JOHN G. LYON, of Pittsburg, in the county of Allegheny and State of Pennsylvania, have invented a new and useful

- 5 Design for Ash- Receivers; and I do hereby declare the following to be a full, clear, and exact description thereof.

My invention relates to a design for ash-receivers. Its leading features are indicated in 10 the following description and claims.

It comprises the combination of two parts—a cup or vessel and a saucer or dish at its base.

The accompanying drawings illustrate my invention.

- 15 Figure 1 is a side elevation of a glass article embodying the design. Fig. 2 is a vertical axial section of Fig. 1.

Like letters of reference indicate like parts in each.

- 20 In the drawings, A represents the cup or holder, which is vertical and hollow. At the bottom of the holder A is the dish or saucer B, constituted by prolongation of the peripheral lines of the base of the holder, which extend for a distance downward and outward in regular curves, thus constituting the concavity 25 b, and from the base of said concavity extend upward and outward in curved lines to the rim

of the saucer. The concavity b is ornamented with a striated pattern. This is a preferable 30 form, because it imparts a remarkably graceful and unique appearance to the article.

The under side of the saucer B and the outside of the holder A are shown in the drawings to be provided with a raised pattern. 35

I claim—

1. The design for ash-receivers, consisting in the hollow cup A, having vertical sides, and the dish B, whose radial lines extend in curves from the base of the cup A downward and outward, thus constituting the concavity b, and from the base of said concavity curve upward and outward to the rim of the dish, substantially as shown and described. 40

2. The design for ash-receivers, consisting of the hollow cup A, having vertical sides, and the dish B, having a concavity, b, at the base of the cup A, the whole being provided with a raised pattern, substantially as shown and described. 45

In testimony whereof I have hereunto set my hand this 29th day of November, A. D. 1886.

JOHN G. LYON.
